CLAIM

The ornamental design for a hair dryer, as shown and described.

DESCRIPTION

FIG. 1 is a perspective view of a hair dryer showing my new design;

FIG. 2 is a left side elevational view thereof shown on an enlarged scale;

FIG. 3 is a bottom plan view thereof;

FIG. 4 is a top plan view thereof;

FIG. 5 is a rear elevational view thereof;

FIG. 6 is a right side elevational view thereof; and

FIG. 7 is a front elevational view thereof.

The cord portion of the design is shown broken away in FIGS. 1, 2, 3, 5, 6 and 7 for ease of illustration.
